UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SWITCH-SOCKET FOR ELECTRIC LAMPS.

1,025,237.

Specification of Letters Patent.

Patented May 7, 1912.

Application filed June 28, 1909. Serial No. 504,735.

To all whom it may concern:

Be it known that I, REUBEN B. BENJAMIN, a citizen of the United States, residing at Chicago, in the county of Cook and State 5 of Illinois, have invented new and useful Improvements in Switch-Sockets for Electric Lamps, of which the following is a full, clear, concise, and exact description, reference being had to the accompanying drawing, forming a part of this specification.

This invention relates to improvements in sockets for receiving and supporting electric lamps, the principal object of the invention being the simplification and improvement 15 of the switch mechanism.

In the accompanying drawings, Figure 1 is a front elevational view of the device; Fig. 2 is a bottom plan view, looking into the lamp-holding sleeve; Fig. 3 is a top 20 plan with the cap removed to afford access to the binding terminals; Fig. 4 is a bottom plan view with the lamp-holding sleeve and casing omitted; Fig. 5 shows a vertical section taken on the line 5—5 of Figs. 1 and 2 25 looking in the direction of the arrows; Fig. 6 is a vertical sectional view, the casing being omitted and the section being taken on the line 6—6 of Fig. 4 looking in the direction of the arrows; Fig. 7 is an enlarged 30 sectional view illustrating the switch mechanism, the section being taken on the line 7—7 of Fig. 4 looking in the direction of the arrows, the switch being open; Fig. 8 is a view similar to Fig. 7, but shows the switch 35 closed; and Fig. 9 shows a section taken on the line 9—9 of Fig. 4 looking in the direction of the arrows.

In these several figures, in which like reference numerals indicate the same parts 40 throughout, 10 is a base of porcelain or other insulating material, on the lower side of which is secured a threaded lamp-receiving shell 11, the base being formed with a chamber 12 in which is located the switch mechanism. A casing shell is provided and is made in two parts 13 and 14, the part 13 being tubular and having a portion 15 of enlarged diameter, while the part 14 consists 45 of a cap arranged to telescope over the larger end 15 of the tubular part. The porcelain base 10 is disposed within the enlarged portion 15 of the tubular member of the casing, the threaded lamp-receiving shell 11 extending downward into the 50 smaller portion of this tubular member.

The invention is shown as applied to what is usually termed an angle socket, that is, a socket in which the bushing by means of which the device is supported extends at an angle with the axis of the lamp-holding 60 shell instead of, as is more often the case, being arranged to extend in line therewith. It is, however, to be understood that the particular form of switch mechanism, as well as some of the other features claimed in this application, may be applied as well to the ordinary straight socket.

The angle socket casing herein shown is provided with a square embossment 16 extending laterally from the side of the tubular member of the casing, and to this embossment is secured the supporting bushing 17. The cap 14 has its edge cut away at 18 to accommodate the embossment 16 when the cap is placed in position.

An insulating disk 19, formed of vulcanized fiber or the like, lies in the bottom of the cup-shaped threaded lamp-receiving shell 11, and through this disk and a similar disk 20 of mica extend a pair of securing screws 21 and 22, these screws having their heads sunk in depressions provided for that purpose in the upper side of the insulating base. Suitable nuts 21^a and 22^a are provided upon the lower ends of the screws 21 80 and 22, the screws and nuts thus serving to retain the threaded shell in position on the base. The cavity 12 in the lower side of the base thus has its open lower side closed by the bottom of the cup-shaped lamp-receiving shell, so that a chamber for the switch mechanism is formed, the lower side of 85 which is the metal of the lamp-receiving shell. The center contact for engagement with the inner terminal of the lamp consists 90 of a Z-shaped plate 23 having an enlarged portion at one end so located as to engage the inner terminal of the lamp, while its opposite end is clamped under the head of a screw 24 and thereby brought into electrical 95 communication with a binding plate 25 on the upper side of the base, which plate 25 carries a binding screw 26. The plate 25 is depressed below the level of the upper surface of the base, being located in a cavity 100 from which leads a channel 27 extending to a notch 28 formed in the edge of the base and located in line with the outlet bushing 17, in order that a feed wire leading into 105 the device and attached to the binding 110

screw 26 may be accommodated. Leading into the notch 28 is a second channel 29 which extends into a cavity in which is located a second binding plate 30 provided with a binding screw 31. The binding plate 30 is held in place by a screw 32 which extends through the base, the plate 30 and one leg of a U-shaped plate 33, this U-shaped plate being located in the switch chamber and having a lug 34 extending laterally therefrom for receiving the holding screw 32. The plate 33 has its free end 35 provided with a lateral extension 36 on each side thereof, as clearly shown in Figs. 7 and 8. A bridge block 37 is arranged to span the space between the shell 11 and the resilient free end 35 of the plate 34, when turned to the "on" position as shown in Fig. 8, and thus complete the circuit by establishing communication between the shell 11 and the binding screw 31. For turning the bridge block 37 to the "on" or "off" position as desired there is provided a key 38 which is mounted on a shaft 39, the shank 40 of the key being inserted through an opening provided for that purpose in the side of the tubular casing shell. The bridge block 37 is provided with a slot of peculiar form in which work a pair of wing-like extensions 41, 41 projecting laterally from opposite sides of the shaft 39.

Heretofore in switch mechanism adapted for use in incandescent lamp sockets it has sometimes been provided that the bridge block should span the space between two spring contacts both of which have movement toward and away from the shaft on which is mounted the bridge block. In such cases the bridge block is not arranged to have longitudinal or other bodily movement on the shaft, but is usually adapted to have some turning movement with respect to the shaft so that there is a certain amount of lost motion between the shaft and the bridge block. This lost motion is provided for in order that the movement of the bridge block in opening the switch will be delayed until the key has been turned far enough to positively move the switch block, whereupon the block will, after passing a certain point, snap off with a sudden forward movement and break the circuit with sufficient quickness to prevent destructive sparking. In other cases the switch block has been made to span the space between a fixed contact and a yielding one, as in the present device, but in such a case it becomes necessary to permit the block to have a certain amount of movement other than rotary. This movement has formerly been provided for by mounting the switch shaft or spindle in an elongated bearing at the end thereof which was nearest the bridge block, or by providing elongated bearings at both ends of the shaft. In the present device the bearings

for the shaft 39 are provided in the plate 34 by forming an aperture through an upturned end 42 on the plate 34 and a similar aperture through the part 43 of the plate 34 which connects the free end with the stationary part of said plate. The necessary endwise movement of the block 37 is provided for by elongating the opening in the block in which the shaft works. Were this opening simply a slot of uniform width and of substantially the same width as the diameter of the shaft there would not be a sufficient amount of lost motion between the shaft and the block unless the shaft were given an undesirably large diameter. Furthermore, and of greater importance, if the block worked over on the shaft so that the end of the projection 41 approached or engaged the end of the slot there would be a tendency for the block to stick when it was attempted to turn the switch from the "off" to the "on" position. By the formation which I have adopted for this slot, and shown in the drawings of this application, a tendency is given the block to return to middle position when the shaft is revolved to close the switch. This slot has in outline the form of two circles tangent to each other or slightly overlapping, connected by a straight portion having a width substantially equal to the diameter of the shaft. Suppose the block to be moved over so that the end of the projection 41 engages the end of the slot, and suppose the switch to be open. If, now, the key be turned to close the switch, the end of the projection will engage the curved end of the slot and will exert a cam-like effect which results in the movement of the block longitudinally in the direction to center the same on the shaft.

By forming the opening in the bridge block as an elongated slot and curving the ends of this slot I am enabled to employ a very simple construction for the other parts of the mechanism. It will be observed that the switch mechanism of this socket is extremely simple and can be economically manufactured.

Having thus described my invention, what I claim as new and desire to secure by Letters Patent, is:

1. The combination with a base having a cavity therein; a plate in said cavity, said plate having an upturned lug at each end and one of said lugs having a spring extension projecting over said plate normally parallel therewith; said extension forming a switch contact; a second switch contact; a shaft rockably mounted in said lugs; a bridge plug carried by said shaft and arranged to make connection between said switch contacts upon movement of the shaft; and means for imparting the requisite movement to said shaft.

2. The combination of a base having a

- cavity in the lower side thereof; a lamp-receiving shell secured to said base so as to close the lower side of said cavity; a plate in said cavity, said plate having an upturned lug at each end, and one of said lugs having a spring extension projecting over said plate normally parallel therewith, said extension forming a switch contact; a shaft rockably mounted in said lugs, a bridge plug carried by said shaft and arranged to make connection between said extension and said lamp-receiving shell upon movement of said shaft; and means for imparting the requisite movement to said shaft. 20
- 5 10 15 20 25 30
- 15 3. The combination of a base having a cavity in the lower side thereof; a lamp-receiving shell secured to the lower side of said base and closing the lower end of said cavity; a binding terminal upon the other
- side of said base; a plate in said cavity, said plate having an upturned lug at each end and one of said lugs having a spring extension projecting over said plate normally parallel therewith, said extension forming a switch contact; a shaft rockably mounted in 25 said lugs; a bridge plug carried by said shaft and arranged to make connection between said shell and said extension upon movement of the shaft; and means for imparting the requisite movement to the shaft. 30
- In witness whereof, I have hereunto subscribed my name in the presence of two witnesses.
